LOOSE LEAF BINDER

Filed June 17, 1926

UNITED STATES PATENT OFFICE.

CLAUDE ST. CLAIR MULLINS, OF FLUSHING, NEW YORK.

LOOSE-LEAF BINDER.

Application filed June 17, 1926. Serial No. 116,506.

This invention relates to binders for loose leaves, and relates particularly to a binder adapted to hold large sheets of paper, maps or documents without tearing or mutilating the same, and which will permit ready removal of the individual papers or maps if desired, and also permit the insertion of additional papers or maps without disturbing the others already in the binder.

Binders intended for holding large sheets of paper and relatively large maps such as insurance maps, must be rugged in construction and must also be sufficiently flexible to prevent injury on account of the heavy weight of the documents which they contain. My improved binder provides an improved means for holding the sheet-retaining posts in the covers by means of a metal reenforcement inserted in the back of the covers, so constructed that it affords great strength. It possesses sufficient resiliency to permit the book, comprising the enclosed maps and covers, to be readily opened and closed without injury, and to provide easy access to the individual sheets either for reference or for removal. Covers are attached to the metal reenforcing by an improved arrangement of the canvas retaining strip that is attached to the covers and the back so that a durable and flexible hinge is provided between the covers and the back of the book. Also means are provided for holding the sheets in adjusted position with respect to the binding post so that mutilation of the sheets by tearing or otherwise, will be avoided when the book is handled, and particularly when it is filled completely or approximately to its capacity, and the covers are quickly opened for inspection of the contents.

Various other objects and advantages of the invention will be obvious from the following particular description of one form of device embodying the invention or from an inspection of the accompanying drawings; and the invention also consists in certain new and novel features of construction and combinations of parts hereinafter set forth and claimed.

In the drawings:

Fig. 1 shows a sectional view through a loose leaf binder embodying features of the invention;

Fig. 2 shows a portion of the binder in open position with one end of the back portion broken away to show the reenforcement; and

Fig. 3 shows a plan view of the binder in open position.

In the following description and in the claims parts will be identified by specific names for convenience, but they are intended to be as generic in their application to similar parts as the art will permit.

Referring to the drawings, the binder comprises two units, the cover or binder proper, and the securing means therefor mounted within the cover. The cover comprises the two flat leaves or sides 10 and 11 of any desired size, preferably made from a plurality of heavy sheets of press board 12 and 13 or other suitable material, and a curved back 14, both the sides and back being enclosed by a stout outer facing 15 of canvas or similar material. The back 14 has one or more filler strips 16 mounted thereon and extending lengthwise thereof, which hold the sides permanently spaced a definite distance apart. A single filler strip has been shown by way of illustration. However, it is obvious that any desired number may be employed depending upon the thickness of the strip and the space to be filled.

Secured to the back of the binder, preferably to the filler piece 16, is a metal frame or casing 17, that is, generally speaking, trough-shaped or U-shaped in section. This metal frame or casing extends lengthwise of the back but is narrower than the adjacent filler piece 16, both ends of which extend beyond the base 18 of the frame 17, forming abutments for a purpose hereinafter described. The arms 19 and 20 of the frame or casing extend at right-angles to the base 18 substantially parallel with the sides of the binder in their closed position, and the outer or front edges terminate in beads 21 and 22 which may be interrupted at intervals to form notches 23 to receive the binding pieces, as hereinafter described.

The metal frame or casing 17 is reenforced by reenforcing angle plates 24 and 25 at both corners, each of the said reinforcements being secured to the adjacent arm of the metal frame 17 in a suitable manner, as by rivets 26.

The hinge between each cover and the back and between each cover and the metal frame or casing, is formed by stout strips 27 and 28 of flexible material such as canvas. The outer strips 27 may be integral with the facing 15 of the cover, or as shown herein may be a separate piece having portions 29

2
and 30 inserted between the facing 15 and cover 10 and between the facing 15 and back 14 respectively. The other or inner strip 28 is a separate piece which is secured to the 5 inside of the cover, and extends backward toward the back of the binder so as to overlap the hinge portion of the outer strip 27, and is then bent downward and forward and over the adjacent arm 19 or 20 of the metal 10 frame or casing, thereby enclosing the bead 21 or 22 on the front edge of the metal arm, suitable openings being made in the canvas to correspond with the notches 23 formed in the beads. From the bead 21 or 22, the inner 15 strip 28 is extended to cover the portion 31 of the reenforcing strip 24 or 25 which is riveted to the arm of the frame, and a strip of paper or canvas 32 covers the portions of the reenforcing strips which engage the base 20 18 of the frame. Near the edge of the cover the outer and inner strips may be sewed together forming a seam 33 running the length of the binder.

A suitable space remains between the rear 25 edge of the canvas hinge and the abutments formed on the back fillers, and a suitable flexible filling material 34 is inserted in this space which may be in the form of a rope or twine which forms a fulcrum between the 30 covers and the back. This fulcrum point is arranged outside of the arms 19 and 20 but adjacent to the base 18 of the frame, whereby it provides the maximum resistance against bending the frame when the covers 35 are open. The rope or other filling material may extend transversely across the back at each end of the frame as shown at 35.

The notches referred to as formed in the 40 edges of the beads receive a plurality of bolts or binding pieces, 36 shown three in number, for holding the sheets 37 in the binder. Each binding piece is provided with perforations 38 at either end, as clearly 45 shown in Fig. 2, and rods extend through these perforations and the beads, to hold the binding pieces removably in position in the binder. The diameter of each binding piece is preferably substantially uniform from end to end, with one end portion preferably unthreaded and the opposite end portion threaded for a suitable distance to receive a 50 clamping nut.

The sheets to be bound are perforated 55 along the binding edge in a well-known manner to receive the binding pieces. An angle clamping plate 39 is mounted on these binding pieces, and for this purpose has one of its sides provided with perforations, and its other side bent at an angle thereto to engage the edges of the sheets which are bound in the book. A clamping nut 40 is threaded 60 on each bolt to hold the clamping plate and sheets in position.

In operation, the leaves which are to be 65 bound are placed in a pile with the punched

edges along the same side. The clamping plate is then applied with the projecting side engaging the edges of the sheets, and the bolts are then inserted preferably with the unthreaded portions lowermost, and are so 70 positioned that the apertures at the ends are in alignment. The clamping means are then applied to each bolt.

The cover is now opened and the securing means unit positioned therein. A rod is 75 then inserted through one bead and through the aligned apertures of the bolts. The cover is then closed and the other bead is held so that it is in alignment with the apertures in the other ends of the bolts, and the second rod, such as shown in Fig. 2, is then inserted. It is obvious that sheets may be removed from either side of the binder by withdrawing the rod from either the threaded or unthreaded ends of the bolts as desired. 85

In my improved construction the hinge, which is formed of a plurality of layers of strong material such as canvas, is practically indestructible. The hinge is furthermore protected against injury in ordinary use or 90 handling by means of the yielding backing which is mounted adjacent to the hinge between the rigid metal frame or casing and the abutment provided by the extending ends of the filler pieces, forming a part of the 95 back of the binder. The inner hinge strip extends rearwardly until it preferably contacts with this backing piece, whereby maximum flexibility in the hinge is secured, and it also provides a stop or abutment against 100 forward displacement of the backing. Consequently, maximum movement of the sides of the binder is permitted without injury or strain to the metal frame or the back of the book. The binding piece may be detachable 105 at both ends, so that maps or other heavy documents may be inserted either at the top or the bottom, whichever may be more convenient. The maps, documents or other articles, are further protected by means of the angular backing plate which is loosely mounted on the binding piece and is automatically adjusted to the quantity of documents in the binder. 110

While I have shown and described and 115 have pointed out in the annexed claims certain novel features of the invention, it will be understood that various omissions, substitutions and changes in the forms and details of the device illustrated and in its operation may be made by those skilled in the art without departing from the spirit of the 120 invention.

Having thus described my invention, I 125 claim:

1. A binder for loose sheets, documents and the like, comprising a curved back and sides hinged to the back, a filler piece secured to the back and providing a flat surface substantially at right angles to the sides 130

- in closed position, a metal frame secured to the flat surface provided with integral forwardly extending arms substantially at right angles to the facing of the back and substantially parallel to the covers in closed position, an angular re-enforcing sheet for each of said arms secured to said frame, and means detachably secured to said arms for attachment of a plurality of separate sheets.
2. A binder comprising a metal frame having two arms, means for detachably securing metal posts to said frame arms, an outer back rigidly secured to the frame and covers each hinged to said back by flexible strips, one of said strips being secured to the cover and to the back on the outside thereof, and the other strip being secured to the cover on the inside thereof and to one side of one of the arms of said frame, and a fibrous member positioned between said metal frame and said first mentioned strip.
3. A holder for loose leaves comprising back and side members, a metal frame secured to said back and having flanges extending forwardly substantially parallel with the side members, the edges of said flanges having notches formed therein, a separable binding unit comprising a plurality of perforated bolts projecting within said notches, each of said bolts having means adjustably positioned thereon for exerting binding pressure on the leaves, and a retaining rod extending through and guided by each flange edge and extending through the perforations in said bolts, a flexible strip connecting said back and each of said side members, a fibrous member adjacent the hinge portion of said side member and being held against forward displacement by a loop formed from said flexible strip secured to said side member and said metal frame.
4. In a binder for loose sheets, documents and the like, the combination with metal posts of a rigid back including a filler piece and a metal frame, said frame having arms secured to the posts, and covers each hinged to said back by flexible strips, one of said strips being secured to the cover and to the back on the outside thereof, and the other strip being secured to the cover on the inside thereof, and to both sides of one of the arms of said frame.
5. In a binder for loose sheets, documents and the like, the combination with metal posts of a rigid back including a filler piece and a metal frame, said frame having arms secured to the posts, and covers each hinged
- to said back by flexible strips, one of said strips being secured to the cover and to the back on the outside thereof, and the other strip being secured to the cover on the inside thereof and to one side of one of the arms of said frame, and a fibrous member positioned between said metal frame and said first mentioned strip.
6. In a binder for loose sheets, documents and the like, the combination with metal posts of a rigid back including a filler piece and a metal frame, said frame having arms secured to the posts, and covers each hinged to said back by flexible strips, one of said strips being secured to the cover and to the back on the outside thereof, and the other strip being secured to the cover on the inside thereof and to both sides of one of the arms of said frame, and a fibrous member positioned between said metal frame and said first mentioned strip.
7. In a binder for loose leaves, documents and the like, the combination with metal posts of a rigid back including a filler piece and a metal frame, said frame having arms secured to posts, an angular re-enforcing sheet for each of said arms secured to said frame, said back being hinged to each of said covers by flexible strips, one of said strips being secured to the cover and the back on the outside thereof, and the other strip being secured to the cover on the inside thereof, and to one side of one of the arms of said frame, and to one side of the corresponding angular re-enforcing sheet.
8. In a binder for loose leaves, documents and the like, the combination with metal posts of a rigid back including a filler piece and a metal frame, said frame having arms secured to posts, an angular re-enforcing sheet for each of said arms secured to said frame, said back being hinged to each of said covers by flexible strips, one of said strips being secured to the cover and the back on the outside thereof, and the other strip being secured to the cover on the inside thereof, and to one side of one of the arms of said frame and to one side of the corresponding angular re-enforcing sheet, and a fibrous member positioned adjacent said back and metal frame.

In testimony whereof I have hereunto set my hand and seal.

CLAUDE ST. CLAIR MULLINS.
